UNITED STATES PATENT OFFICE.

CHARLES ALGERNON PARSONS, STANLEY SMITH COOK, AND LOUIS MORTIMER DOUGLAS, OF NEWCASTLE-UPON-TYNE, ENGLAND; SAID COOK AND SAID DOUGLAS ASSIGNEES TO SAID PARSONS.

GEARED TURBINE INSTALLATION.

1,322,814.

Specification of Letters Patent. Patented Nov. 25, 1919.

Application filed November 5, 1918. Serial No. 261,308.

To all whom it may concern:

Be it known that we, CHARLES ALGERNON PARSONS, STANLEY SMITH COOK, and LOUIS MORTIMER DOUGLAS, all subjects of the King 5 of Great Britain and Ireland, and all residing at Heaton Works, Newcastle-upon-Tyne, in the county of Northumberland, England, have invented certain new and useful Improvements in Geared Turbine Installations, 10 of which the following is a specification.

The present invention relates to geared turbine installation, especially for ship propulsion, and has for its object to arrange the drive in such a manner that deflection of the 15 pinion shaft due to the torque is minimized.

It has already been proposed to mount a turbine at either end of a pinion shaft so that each turbine drives the pinion through the end adjacent to it. This arrangement, 20 however, leads in many cases to an unsatisfactory distribution of the power units so that the arrangement of the engine room is inconvenient.

The present invention consists in placing 25 the two turbines on the same side of the pinion shaft, the near turbine being connected to the near end of the pinion shaft, while the other turbine drives the opposite end of the pinion shaft through a small diameter intermediate shaft passing through central holes in the near turbine rotor and in the pinion shaft.

The invention also consists in the improved geared turbine installations herein- 35 after described.

Referring to the accompanying drawings:—

Figure 1 shows a high pressure turbine and low pressure turbine in series driving 40 a common pinion in accordance with this invention.

Fig. 2 shows a similar arrangement in which the axial position of the rotors is controlled by the intermeshing teeth of the 45 gears;

Fig. 3 shows a four turbine single reduction system.

Fig. 4 shows a four-turbine double reduction system.

50 In carrying the invention into effect as illustrated in Fig. 1, two turbines *a*, *b*, are provided co-axial with the pinion shaft and situated at the same side of it. The near

turbine rotor *c* is mounted on a sleeve *d* and is adapted to be connected by a suitable sliding coupling *e* to the hollow shaft *f* of the pinion *g*. The second turbine *b* is adapted to be connected by a suitable coupling *h* to an intermediate shaft *k* of small diameter passing axially through the hollow shaft *d* of the turbine rotor *c* and the hollow pinion shaft *f* and connected at its far end by a coupling *l* to the hollow pinion shaft.

By this arrangement the drive from the two turbines is taken to the two ends of the 65 hollow pinion shaft. The central holes in the hollow rotor and pinion shafts are so bored as to support the central shaft at reasonable intervals along its axis. Thrust blocks *m*, *n* and expansion couplings may 70 be provided; or, according to the example shown in Fig. 2, these may be dispensed with, the longitudinal position of the turbine rotors being determined by the intermeshing of the pinion gear teeth with the 75 teeth of the gear wheel as described in our British Patent specification No. 15959 of 1917.

In the form of the invention shown in Fig. 3 which shows a four turbine single 80 reduction arrangement, each of the double pinions 1, 2, is driven by two turbines; the gear wheels are placed between the double pinions so that a symmetrical arrangement is obtained. The two ahead turbines 11, 12, 85 are arranged in series and the steam is led from the exhaust of turbine 12 to two double flow turbines 13, 14, arranged in parallel. The astern turbines are in parallel and are in series with the two astern double 90 flow turbines respectively. The axial position of the rotors is controlled by thrust blocks 5, 6.

According to another example of the invention illustrated in Fig. 4, adapted to a 95 four-turbine double reduction installation, each of the primary pinions 1, 2, is driven by two turbines arranged as above described. The primary gear wheels 19, 20, may be placed between the secondary pinions 21, 100 22 so that a symmetrical arrangement is obtained. The four ahead turbines in this installation may be arranged in series and both pinions may be driven under astern conditions. The longitudinal positions of the 105 turbine rotors are in this example deter-

mined by the intermeshing gears, the steam flow being in opposite directions in the two turbines driving each pinion.

It will be seen that many other arrangements according to the invention can be designed, the essential feature being that the two turbines driving any pinion are placed on the same side of it, the near turbine being connected to the hollow pinion shaft 10 while the more remote turbine drives the far end of the hollow pinion shaft by means of a shaft passing through the near turbine rotor and the hollow pinion shaft.

Having now described our invention, what 15 we claim as new and desire to secure by Letters Patent is:—

In a geared turbine installation of the

type in which two turbines drive a common pinion, in combination, a hollow pinion shaft, two turbines on the same side of and 20 coaxial with the said pinion shaft, the near turbine being connected to the near end of the pinion shaft, a small diameter intermediate shaft, the other turbine being connected to the opposite end of the pinion shaft 25 through said small diameter intermediate shaft which passes through the near turbine rotor and in the hollow pinion shaft.

In testimony whereof we have signed our names to this specification.

CHARLES ALGERNON PARSONS.
STANLEY SMITH COOK.
LOUIS MORTIMER DOUGLAS.
